FIG.-3

FIG.- 4

FIG.- 5

FIG.-6

FIG.-7

FIG.-8

FIG. 1 is a front perspective view of a wing glider showing our new design;

FIG. 2 is a rear perspective view of the wing glider of FIG. 1;

FIG. 3 is a side perspective view of the wing glider of FIG. 1;

FIG. 4 is a side perspective view taken from the rear of a wing glider showing a modified form of our new design;

FIG. 5 is a side view taken from the front of the wing glider of FIG. 4;

FIG. 6 is a rear view of the wing glider of FIG. 4;

FIG. 7 is a bottom perspective view taken from the front of the wing glider of FIGURE 4; and

FIG. 8 is a front perspective view of the wing glider of FIGURE 4.

The dominant features of the design reside in the portions shown in full lines and the broken line representation of cargo in FIGURE 6 is for illustrative purposes only.

We claim:

The ornamental design for a wing glider, as shown and described.
